ANTI-BLAST AND ANTI-SUCTION AIR VALVE
FOR ATOMIC BOMB SHELTER
Elmathan K. Nelson, 4640 Pacific Highway,
San Diego 10, Calif.
Filed Dec. 15, 1961, Ser. No. 159,557
1 Claim. (Cl. 137—516.25)

This invention generally relates to atomic bomb shelters and more particularly to the anti-blast and anti-suction valve mechanism for the air intake and air exhaust lines of said shelters.

An object of the invention is to provide an improved and safer method of preventing the radiation, heat and overpressure from nuclear explosions from entering the survival chamber of the basic bomb shelter and likewise prevent the ensuing suction following a blast from sucking the air or oxygen from the survival chamber or living area of the basic bomb shelter.

The drawing shows inside elevation a cross section of the air intake or air exhaust valve assembly.

Referring specifically to the drawing, members 1, 2 and 3 are standard steel pipes. The tank 20 forms a valve chamber and includes standard end sections 6 and 7. Mounted within tank 20 is a fixed pivot member 16 which as shown is adjustable as to height. Pivotedly mounted on member 16 is a non-corrosive steel chain 17 that supports a non-corrosive steel ball 18 which acts as the valve member. Cooperating with said valve member are a pair of valve seats shown at 14 and 15. Connected to the valve chamber tank 20 by pipe 2 is a blast absorption tank 19 which includes the standard tank ends 4 and 5. Within tank 19 are mounted a plurality of baffle plates 8 and 9 which include circular holes corresponding in I.D. to that of the standard steel pipe members 1, 2 and 3. Further, arrows 12 and 13 indicate the direction of air flow for intake with exhaust flow being in the reverse direction.

The non-corrosive steel ball or equivalent 18 (it could be a flat plate with seats ground accordingly to fit) is supported by a non-corrosive steel chain 17. This ball 18 is so situated in the valve chamber 20 and so weighted that it will permit the normal flow of air to pass through the chamber 20 without closing. This is accomplished by delicately weighting the ball 18 to remain in an open position at a desired maximum normal air velocity. Whenever over pressure beyond this point of normal velocity develops the accelerated flow of air will cause the ball 18 to seat against the ground seat 15. This movement is accelerated by the air pressure against the ball 18 and by the creation of a vacuum in front of the ball's movement through the use of wide seats 14 and 15. As soon as the overpressure drops to normal the valve or ball 18 will swing open to its neutral position. As soon as the under-pressure or near vacuum develops following the initial blast waves the ball 18 will swing to its opposite closing position and seat on the ground seat 14. As soon as the external air pressure returns to normal the valve or ball 18 will again return to its neutral position.

In the event of failure of the ball 18 to open and also for routine cleaning and inspection there will be provided a removable plate (not shown) for freeing or cleaning the valve or ball 18. Inasmuch as said removable plate is of quite simple construction and may be accomplished in various manners it is not felt that the details are of sufficient import to add to the value of the invention.

Due to the high velocity of the initial shock wave from a nuclear explosion (1400 to 4000 ft. per second) it has been determined that the valve or ball 18 would not have time to activate itself and close in sufficient time to protect the occupants of the basic bomb shelter. Further it has

2

been determined that this initial shock wave does not push masses of air with its action. Therefore the installation of the anti-blast chamber 19 to the air line just ahead of the valve closure chamber 20 will accomplish this purpose by diffusing the initial blast to force such an extent that the secondary wave from the blast travelling at approximately the speed of sound will activate and close the valve ball 18 in sufficient time. Baffle plates 8 and 9 in the chamber 19 are used to confuse and diffuse the initial high velocity over pressure.

It is contemplated that the entire assembly shown in the drawing will be installed in the entranceway to the basic bomb shelter in an absolute plumb position in order that the valve or ball 18 will be suspended in a truly neutral position. It may however prove desirable to separate the two chambers 19 and 20, placing the valve closure chamber 20 in some accessible location and burying the initial anti-blast chamber 19 at some point in the air line ahead of the valve closure chamber 20.

Manufacture of the complete assembly will be accomplished generally through the use of standard pressure tank ends of the proper rating and assembly will be accomplished by the means of continuous certified welds. Valve seats 14 and 15 will be machined after welding the standard steel pipe sections in place and finally grinding and lapping these seats to required tolerances. Balance of assembly will be rather obvious and simple to those skilled in the trade.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

This application is a continuation-in-part of applications Serial No. 143,716, filed October 9, 1961, and Serial No. 155,912, filed November 30, 1961, both abandoned.

Having thus completely and fully described the invention, what is now claimed as new is as follows:

In combination an anti-blast and anti-suction air valve and blast absorption chamber for an air line leading to a bomb shelter comprising; a first pressure tank, pipe means extending into said tank from opposite ends thereof, the ends of said pipe means in said tank including valve seats, means forming a fixed pivot in said tank, a steel chain having one end fixed to said pivot means, a steel valve ball fixed to the other end of said chain and extending therefrom to a position between said seats by the force of gravity, means forming an absorption chamber having one end connected to one of said pipe means comprising; a heavy duty pressure tank having a pipe connected to said opposite end, and a plurality of apertured baffle plates mounted in said pressure tank whereby said valve swings in an arc of a pendulum to a closing position on one or the other of said seats during the overpressure or negative pressure phase of an explosion and whereby said baffle plates are arranged to break up or diffuse the initial shock wave resulting from said explosion.
